UNITED STATES PATENT OFFICE.

CLARENCE W. COLEMAN, OF WESTFIELD, NEW JERSEY; KATHERINE COLEMAN, ADMINISTRATRIX OF SAID CLARENCE W. COLEMAN, DECEASED, ASSIGNOR TO THE HALL SWITCH & SIGNAL COMPANY, A CORPORATION OF MAINE.

SIGNAL SYSTEM.

1,157,845.

Specification of Letters Patent.

Patented Oct. 26, 1915.

Application filed March 16, 1908. Serial No. 421,314.

To all whom it may concern:

Be it known that I, CLARENCE W. COLEMAN, a citizen of the United States, residing at Westfield, in the county of Union and 5 State of New Jersey, have invented a certain new and useful Improvement in Signal Systems, of which the following is a specification, reference being had therein to the accompanying drawings, forming part 10 thereof.

My invention relates to automatic electric block signal systems for railroads, and is designed particularly for use in connection with electric railroads, although it is 15 applicable also to steam railroads.

One object of the invention is to produce a simple and reliable signal system for operating in connection with double-track railroads, particularly where home signals and 20 distant signals are used in conjunction, or both home and distant indications are given, and to this end the invention comprises various features of arrangement and construction, hereinafter more particularly described, by which the number of line wires required is reduced to a minimum and the 25 signal-controlling apparatus is simplified.

The signal-controlling relays are energized by alternating or other periodic currents, 30 and an important feature of the invention consists in means whereby the home and distant signals are selectively controlled by reversing the phase of the current in the line circuit and line relay.

Another feature of the invention is a means for reducing the magnetic reluctance of the magnetic circuits surrounding the track rails at or near the termini of the signaling blocks, which acts so as to increase the effect of the track-circuit currents 40 upon the relays or translating devices controlled by the track circuits.

More specifically, one embodiment of the foregoing broad feature of the invention is an improved arrangement used in connection with the inductive track coil by which its efficiency is increased through the improvement of the magnetic circuit about the coil and the conducting rails.

50 I will now describe the embodiment of

my invention illustrated in the accompanying drawings, and will thereafter point out my invention in claims.

In the drawings Figure 1 is a diagram of a signal system embodying my invention. 55 Fig. 2 is a side elevation, and Fig. 3 is a transverse section, of a portion of a track coil and the adjacent rail.

The drawings illustrate a complete block with portions of two others, and the two 60 signal stations illustrated are designated respectively as A and B. As the apparatus and circuits are identical at these stations similar reference numbers are used for similar parts, but in the succeeding description the 65 letters A and B are appended, where necessary, to the reference numbers, to indicate the station at which the designated part is located.

The illustrated embodiment of the invention is designed particularly for use in connection with electric railroads in which the rails are used as a portion of the circuit for the traction current, and I have employed the arrangement of continuously- 70 bonded rails, with cross-bonds and inductive track coils at the ends of the blocks, which is disclosed in the application of Clyde J. 75 Coleman, Serial No. 383366, filed July 12, 1907, while I employ alternating or equivalent periodic currents for energizing the line 80 circuits and the relays.

A double track system is illustrated, having a west-bound track 1 and an east-bound track 2. The rails are bonded continuously, 85 and at the junctures between the blocks are heavy cross bonds 3 of negligible impedance. Transmission wires 4 and 5, supplied by a suitable generator 10, furnish alternating current to track-circuit transformers 6 and 7 90 of which the secondaries are connected, respectively, to the west-bound and east-bound rails. The transformers are located substantially at the center of each block, so that the current from each secondary is 95 divided evenly, one-half being transmitted through one rail to the east, through the cross bond 3 at the end of the block, and back by the other rail, while the other half of the current follows a similar path in the 100

western half of the block. These track circuits are normally energized, and they act inductively on track coils 8 and 9 which are located, at the respective ends of each block, close to and parallel with the rails.

The track coils normally energize track relays 11 and 12 which control the line circuit at each end of the block. When a train is in any portion of the block it acts to de-energize one or both of the track coils, since the car wheels and axles act as cross-bonds and divert the alternating currents from the ends of the track circuits, where the track coils are located, and thus the inductive action is interrupted.

The track relays 11 and 12 are of the polarized type, in order that they may respond readily to the comparatively faint currents in the track coils. Each relay has a pivoted armature 13 carrying a contact finger 14 and provided with a coil connected in circuit with one of the track coils. The field coil 15 of the relay is constantly energized, being connected with feed wires 16 and 17 which are energized by a transformer 20 fed by the transmission wires 4 and 5. The currents in the field coils and the armature coils of the track relays agree substantially in phase, so that the armatures tend normally to rotate in a direction to keep the contact fingers in engagement with fixed contacts connected in circuit with the line wires 18 and 22.

The local signal circuits are controlled directly at each station by a line relay 25. The line relay is also of the polarized type, but in addition to the contact finger 26 mounted on the armature and responsive to changes in polarity, it has a contact finger 27 actuated by a neutral armature. In the line relay it is the armature which is constantly energized, by connection of its coil with feed wires 16 and 17, while the field coil is connected in the line circuit. Thus, when the field is energized by a current agreeing in phase with the current in the armature both contact fingers are held in engagement with the fixed contacts, while upon a reversal of phase in the line circuit and the field coil the polarized contact finger 26 drops, the neutral contact finger 27 remaining up, and upon an interruption of the line circuit, the field being deenergized, both contact fingers drop and open circuit.

The signals are of the normal-safety type. They have a normal bias to danger position, but are normally held clear by electric apparatus, which may be of any usual or suitable construction. When either signal circuit is broken, however, the corresponding semaphore rises to danger position.

The home signal 23 is controlled by the neutral contact finger 27, the current passing, from feed wire 16, through wire 33, contact finger 27, fixed contact and wire 34,

and home signal 23, and thence, by return wire 35, to feed wire 17.

The distant signal is controlled by polarized contact finger 26 of the line relay, the current passing, from feed wire 16, through wire 33, contact finger 26, fixed contact and wire 36, and signal 24, and thence by wire 37, through a circuit breaker 38, to return wire 35 and feed wire 17.

Circuit breaker 38 is actuated by mechanical connection with home semaphore 23, being moved to open-circuit position when the semaphore rises. This prevents the possibility of the distant signal remaining at clear when the home signal is at danger. The circuit breaker does not affect the normal operation of the signals, but guards against certain unusual contingencies, such as the breakage of the mechanical connections between the home semaphore and its electric actuating mechanism.

The direction, or phase-relation, of the current in the line circuit with respect to that in the field coils of the line relay 25 is controlled by a pole-changing switch 29 mechanically connected with the home semaphore so that the contact-fingers of the switch are raised and lowered with the semaphore.

The normal line circuit may now be traced. Starting at feed wire 16, station A, it passes through wire 31 to the lower finger of pole-changing switch 29, through wire 32 to line wire 22 and station B, through wire 21^B and wire 19, to the contact finger of track relay 12^B, which is normally raised as above described, thence, through the fixed contact and wire 28 to the field coil of line relay 25^B, thence, through line wire 18, to the fixed contact and contact finger of track relay 11, also normally raised, thence, through wire 30, to the upper finger of switch 29, and back, through return wire 35, to feed wire 17.

The trains operate automatically to set the signals in the rear at danger, both home and distant signals being set at the entrance end of the block occupied by the train, while the distant signal alone is set at the entrance to the next block in the rear. To illustrate this action, suppose a train occupies some portion of the block to the west of A. Owing to the presence of the train the line circuit through the field coil of line relay 25^A is broken, either by track relay 12^A or by the track relay 11 at the other end of the block (not shown) and line relay 25 is thus deenergized, allowing both contact fingers 26 and 27 to fall. Both signal circuits are thus opened, and both home signal 23^A and distant signal 24^A rise to danger position.

The distant signal 24^B is set in consequence of the above-described movement of home signal 23^A. Pole-changing switch 29^A being raised, the phase of the current in line cir-

cuit A—B is reversed. This reversal results in polarized contact finger 26 of line relay 25^B falling so as to open the circuit of distant signal 24^B, which thereupon rises to 5 danger. Neutral contact finger 27 remains up, however, so that home signal 23^B is not affected.

The signal-controlling apparatus for the west-bound track is similar to that for the 10 east-bound track and need not be separately described. An important feature of the invention, however, consists in the elimination of one line wire by using the line wire 22 in the line circuits of both tracks. This wire 15 is connected with track relay 12 of the east-bound track by wire 21, and with the corresponding pole-changing switch by wires 21 and 41, and thus the line circuit of the east-bound track comprises line wires 39 and 22, 20 while the line circuit of the west-bound track comprises wires 18 and 22.

Another important feature of the invention resides in the economy in apparatus and current effected by using the transformer 20 25 as the common source for energizing all the relays, as well as the signal and line circuits, at the signal station, whether those for one track, or, as shown in the diagram, those for both tracks.

30 The arrangement of the track coil illustrated in Figs. 2 and 3 is designed to increase the inductive effect of the rails upon the coil by forming a closed magnetic circuit about the rails and the coil. The wires 35 42 of the coil lie closely against the inside of the web of the rail 43. Angle plates 44 and 45 bear at their upper ends against the head of the rail, and the bases of the angle plates are in contact with yoke plates 46 passing 40 under the rail. Closed magnetic circuits are thus formed through plates 44, the head of the rail, plates 45, and plates 46, and these circuits inclose the track coil and also the rail, with the exception of the rail head.

45 Discontinuous plates are used, as shown in Fig. 2, in place of continuous strips, in order to confine the currents entirely to the rail and, so far as possible, within the magnetic circuits. The plates are secured in place by 50 clamps 47 connected by bolts 48.

It will be noted that the track circuit which supplies current to each relay comprises a comparatively short rail portion, shown in the drawing as co-extensive with 55 the track coil employed in this specific embodiment of my invention, and which must be entirely cut off from the supply transformer by the car wheels in order to wholly deprive the relay of current. Obviously, 60 therefore, it is desirable to make these comparatively short rail portions as short as possible in order to fix the effective termini of the adjacent signaling blocks or track circuits within the smallest possible limits, and reduce 65 to a minimum the unprotected sections

of track between them. To this end the improved magnetic circuits which I have above described as surrounding the track rails are disposed around the said comparatively short portions of the track rails. The effect 70 of this improvement of the magnetic circuits about the said short portions of the rails is to produce an increase of counter electro-motive force and impedance in the said portions, and to make it possible to obtain 75 greater energy in any relay or equivalent device the connections of which are coorganized with one of said comparatively short portions of the track, as aforesaid, in such manner that the said track portion must be 80 entirely cut out of circuit by the car wheels in order that the relay may be wholly deprived of current. For a given energy delivered to the track and a given energy required by the relay, this improvement in the 85 magnetic circuits enables me to attain a substantial reduction in the lengths of said comparatively short portions of the track rails or track circuits; and vice versa, with any given lengths of said portions of the track 90 rails, this improvement in the magnetic circuits enables me to attain a substantial reduction in the amount of energy supplied to the track, or enables me to employ a much less sensitive relay.

Although I have described my invention in its application to a signal system employing semaphore signals it will be apparent that it is applicable to signals or traffic controlling devices of other kinds, and that certain features of the invention are not limited to use in connection with signal systems operating on the normal-safety plan. In general, various modifications may be made in the embodiment of my invention herein described and illustrated in the accompanying drawings without departure from the nature and scope of the invention as defined in the following claims.

I claim:—

1. A block signal system comprising, in combination with a double track, a signal for each track, line circuits controlling said signals, and having one wire in common, means for energizing the line circuits with a periodic current, and means for changing the phase of the current in either line circuit to effect the control of the corresponding signal.

2. A block signal system comprising, in combination with a double track, a signal for each track, normally-closed line circuits controlling said signals and having one wire in common, means for energizing the line circuits with a periodic current, and means for changing the phase of the current in either line circuit to effect the control of the corresponding signal.

3. A block signal system comprising, in combination with a double track, a signal

for each track normally at safety, normally-closed line circuits controlling said signals and having a wire in common, means for energizing the line circuits with a periodic current, and means for changing the phase of the current in either line circuit to set the corresponding signal at danger.

4. A block signal system comprising home and distant signals normally clear, a normally-closed line circuit for controlling the signals, means for energizing the line circuit with a periodic current, both signals being adapted to assume the danger indication when the line circuit is interrupted and the distant signal line being responsive to a change of phase of the current in the line circuit to assume the danger indication, and means for interrupting the line circuit to set both the home and distant signals in unison at danger and for changing the phase of the current in the line circuit to set the distant signal alone at danger.

5. A block signal system comprising home and distant signals, a line circuit, a line relay in the line circuit provided with a polarized circuit controller and an unpolarized circuit controller for selectively controlling the circuits of the distant and home signals respectively, means for energizing the line circuit and the line relay with a periodic current, and means for interrupting the line circuit to set both the home and distant signals in unison at danger and for changing the phase of the current in the line circuit to set the distant signal alone at danger.

6. A block signal system comprising home and distant signals, a line circuit, a line relay in the line circuit provided with a polarized circuit controller and an unpolarized circuit controller for controlling the circuits of the home and distant signals selectively, means for energizing the line circuit and the line relay with a periodic current, and means for changing the phase of the current to activate the polarized circuit controller without affecting the unpolarized circuit controller.

7. A block signal system comprising, in combination with two tracks, line circuits for both tracks having a wire in common, home and distant signals for each track selectively responsive to a change of phase of the current, means for energizing the line circuits with periodic currents, and means for changing the phase of the currents to control the home and distant signals selectively.

8. A block signal system comprising, in combination with two tracks, line circuits for both tracks having a wire in common and normally closed, home and distant signals, normally clear, for each track, the signals being selectively responsive to a change of phase of the current of their respective tracks, means for energizing the line cir-

cuits with periodic currents, and means for changing the phase of such currents to control the home and distant signals selectively.

9. A block signal system comprising signals, a track having continuously-bonded rails and cross bonds at the ends of the blocks forming track circuits, means for energizing the track circuits with a periodic current, inductive track coils, track relays controlled thereby, a line circuit controlled by the track relays, means for energizing the line circuit with a periodic current, and means for changing the phase of said current to effect the control of the signals.

10. A block signal system comprising signal stations, line and track relays at each station, and means for energizing the relays comprising a single transformer at each station connected in multiple with the relays and energizing them constantly with a periodic current.

11. A block signal system comprising signal stations, relays and local signal circuits at each station, a line circuit extending from each station to the station next in rear and controllable by the apparatus of the advance station and arranged in control of the apparatus of the rear station, and a single transformer at each station connected with said relays and circuits in multiple with one another to energize them constantly with a periodic current.

12. A block signal system comprising, in combination with a double track, signal stations, polarized relays at each station for controlling the signals of both tracks, and a single transformer at each station connected in multiple with said relays and energizing them constantly with a periodic current.

13. A signal system comprising a track circuit energized with a periodic current, a portion of a rail of the track circuit being provided with an improved magnetic circuit, and signal-controlling apparatus arranged in inductive relation to said portion of the track circuit and inductively controlled by such current.

14. A signal system comprising a track circuit energized with a periodic current, means applied to portions of both rails of the track circuit to improve the magnetic circuits about such rail portions and augment the inductive effect of the track-circuit current therein, and signal-controlling apparatus arranged in inductive relation to said rail portions and inductively controlled by such current.

15. A signal system comprising a track-circuit energized with a periodic current, signal-controlling apparatus, and a coil connected with such apparatus and located in inductive proximity to a portion of a rail of the track circuit, such portion of the rail having an improved magnetic circuit to increase the inductive effect upon said coil.

16. A block signal system comprising track circuits energized with periodic currents, the rails of the track circuits having improved magnetic circuits near the ends 5 of the blocks to augment the inductive effect of the track-circuit currents therein, and signal-controlling apparatus arranged in inductive relation to said magnetic circuits and thereby controlled by such currents.

17. A block signal system comprising track circuits energized with periodic currents, means applied to portions of the rails of the track circuits adjacent to the ends of 10 the blocks to improve the magnetic circuits about such portions and augment the inductive effect of the track-circuit currents therein, and signal-controlling apparatus arranged in inductive relation to the improved 15 magnetic circuits and thereby controlled by such currents.

18. A signal system comprising a track circuit including the two track rails and a cross-conductor and energized with a periodic current, a portion of the track rails adjacent to said cross-conductor having an improved magnetic circuit to augment the inductive effect of the current therein, and signal-controlling apparatus arranged in inductive relation to said improved magnetic 20 circuit and thereby controlled by such current.

19. A block signal system comprising a continuously-conductive track having cross-bonds at the ends of the blocks and constituting track circuits demarcated by such cross-bonds, coils in inductive proximity to the track rails near the ends of the blocks, signal-controlling apparatus connected with 25 said coils, and means applied to the rails near the ends of the blocks to improve their magnetic circuits and increase their inductive effect on said coils.

20. A signal system comprising conductive 30 track rails, conductors located in inductive relation with the rails, and bodies of magnetic material partly surrounding the rails and said conductors to improve their magnetic circuits and increase the inductive effect between them.

21. A signal system comprising a conductive track rail, and bodies of magnetic material surrounding said rail with the exception of its head to improve the magnetic 35 circuit about the rail.

22. A signal system comprising a conductive track rail, and adjacent electrically-discontinuous bodies of iron applied to the side of the rail and bridging the head and the 40 base thereof to improve the magnetic circuit about the rail.

23. A signal system comprising a conductive track rail, an inductive conductor

located at one side of the rail and between the head and the base thereof, and a plate 45 of magnetic material connecting the head and the base of the rail and inclosing the conductor.

24. A continuous-rail block signaling system comprising track rails having portions 50 of increased impedance, and means for utilizing such increased impedance.

25. A continuous-rail block signaling system comprising track rails having portions 55 thereof near the ends of the blocks of increased impedance, and means for utilizing such increased impedance.

26. In a block signaling system, track rails which are electrically continuous for all currents, said rails having portions of increased 60 impedance, conductors connecting said rails at those portions thereof which are of increased impedance, and means for utilizing such increased impedance.

27. In a block signaling system, track rails 65 having portions thereof at and adjacent to the block limits reinforced to increase their impedance, and means for utilizing such increased impedance.

28. In a block signaling system, electrically continuous track rails having portions 70 thereof at and adjacent to the block limits reinforced by magnetic material between their heads and bases, and passing beneath their bases.

29. A railway signaling system comprising a signal, a relay in control of the signal, a track circuit including the track rails, a source of periodic signal-controlling current therefor, an induction member operatively 75 connected to the relay and disposed in inductive relation to a definite limited portion of the rails and adapted to receive induced currents therefrom and control the relay, and an improved magnetic circuit surrounding 80 said definite limited portion of the rails and comprising material of relatively high magnetic permeability disposed in proximity to 85 said definite limited portion of the rails and 90
